BOX CLOSURE

Robert F. Snyder, East Cleveland, Ohio

Application June 10, 1948, Serial No. 32,237

5 Claims. (Cl. 229—17)

1

This invention relates generally to cartons or containers of the type fabricated by folding thin sheet material such as paper board, and more specifically to such cartons or containers formed with dispensing means in its top which may be closed to retain the contents and maintain it in a sanitary condition.

Cartons of the type to which this invention relates are widely employed for the packaging of granulated materials such as soaps and detergents, and are also employed for the packaging of grain cereals, breakfast foods and the like. In either case it is desirable that some form of dispensing means be provided so that relatively small quantities of the packaged material may be poured from the container. If finely divided materials are carried by the container, it is important that the dispensing arrangement be capable of forming a closure that will prevent accidental leakage. It is equally important that the dispensing arrangement be capable of forming a closure that will maintain the foods in a sanitary condition and preclude the entry of insects.

The principal object of the present invention resides in the provision of a combined dispensing and closure means that has the following features and advantages:

1. A dispensing means that may be readily opened when the package is received from the supplier;

2. A dispensing means that may be readily manipulated, subsequent the initial use thereof, to provide an effective closure;

3. A dispensing means that may be provided without material modification of the blank from which the carton is formed.

Briefly, in one form of the invention the aforesaid objects and advantages are obtained by forming a trapezoidal flap at one side of the carton top with the narrow side thereof articulated. The carton, in such case, is formed in a conventional manner with a rectangular end flap extending inwardly from the associated end panel and underlies the top. In the present invention the end flap may be manipulated to overlie the top flap and underlie the triangular top segments on each side thereof whereby a closure is formed that may be readily opened and resealed.

The manner in which the aforesaid objects and advantages are accomplished by the invention will be apparent from the following detailed description of a preferred embodiment thereof.

In the drawings:

Fig. 1 shows a partially folded blank for the carton;

2

Fig. 2 shows a corner of the carton before the dispensing means has been opened;

Fig. 3 shows the top flap separated from the top at its sides by parting the fracture lines;

Fig. 4 shows the top flap bent back and revealing the end flap disposed thereunder which has been previously glued thereto;

Fig. 5 shows the end flap bent to clear the opening in the carton which is now ready to accommodate the dispensing operation;

Fig. 6 shows a preliminary step in closing the dispensing means;

Fig. 7 shows the dispensing means in its closed or sealed position;

Fig. 8 is a medial section through Fig. 7;

Fig. 9 shows a modified form wherein the carton is manufactured with the top flap pierced from the top, but sealed for shipment by an adhesive tape; and,

Fig. 10 shows the preliminary opening or closing step of the modified form.

Referring to Fig. 1, a typical blank for a carton is shown partially folded and assembled. The carton comprises side panels 10 and 11 and end panels 12 and 13, which may be cemented or glued at the flange 14. The blank includes top segments 15 and 16, and end panels 12 and 13 are customarily provided with end flaps 17 and 18, respectively, which form continuations of the end panels and are bent therefrom. This portion of the blank is conventional, particularly the end flaps 17 and 18. The manner of forming the top may be varied from the construction shown without affecting the mode of operation of the invention.

The only modification of the conventional blank heretofore described, in order to affect one form of my invention, is to provide a generally trapezoidal top flap. This is readily accomplished by scoring the top segments as at 19 for articulation of the flap on the top and by providing fracture lines 20 to facilitate separation or parting of the flap from the top. An adhesive 22 is applied to the end flaps or to the underside of the top, and the parts that are folded down as indicated by the arrows in Fig. 1 complete the sealing of the box. With this structure, the box has the appearance indicated in Fig. 2 and is conventional in structure except for the fracture lines 20 and the articulation line 19 that cooperate to form top flap 21.

When the user wishes to open the carton he merely grasps the top flap 21 and parts the fracture lines, simultaneously breaking the glued connection with the end flap 18. This is shown in

Figs. 3 and 4. The end flap 18 is now exposed and may be readily elevated to clear the top as shown in Fig. 5. The end flap 18 was formerly retained in its fabricated position by the triangular top members 23 adjacent the top flap, but the end flap may now be deformed or bent, during the opening operation to clear the corners 23.

When it is desired to close and seal the dispensing means, the top flap 21 is pushed downwardly in the aperture formed in the top and the end flap 18 manipulated so that its edges slide below the corner segments 23 and above the top flap 21, as seen in Fig. 6. With the edges properly inserted, the end flap 18 tends to spread out and assume its original position, as shown in Fig. 7, though now it will cooperate with the top flap and with the top segments 23 to form an effective interlocked closure that will prevent the discharge of the contents of the carton as well as exclude foreign matter or insects. Thus, it will be seen that by performing a simple additional operation on the blank, a dispensing means is provided that may be easily repositioned after opening to form an effective closure.

When making the blank, instead of forming the top member with fracture lines, as shown in Figs. 1 and 2, it may be preferable to form the top flap so that it is initially free of the top by piercing the top along the lines 30. The box may then be assembled after filling with the top flap and end flap disposed, as shown in Fig. 9. In this form, no glue is applied to the end flap 18 and the box is assembled for shipment with the same disposition of parts that occurs after the dispenser has been opened and closed by the user as heretofore described.

In this construction it is preferable that an additional sealing means be added to maintain the parts in positive relation during shipment and handling, and for this purpose it has been found that a thin band of suitable adhesive tape 32 may be applied to the carton across the joints so that the exposed portion of the end flap 18 as well as the adjacent top segments 23 are covered.

The form just described is in many respects a preferred form in that it does not require any tearing or parting of the fracture lines by the user. It also has an advantage not found in prior closing and dispensing means commonly employed in the trade in that the carton is delivered to the user with the dispensing and closure means in the position they will assume after the carton has been opened and closed. Thus, by examining the carton when he receives it, and when he opens the carton the user is automatically instructed in the proper manipulation of the parts.

It will be understood that the top construction illustrated in Fig. 1 merely represents one arrangement common in the art. Other top constructions may be employed without departing from the essence of the invention and its mode of operation so long as an end flap is provided at the dispensing corner. It will also be apparent that the line from each end of the line of articulation of the top flap and the carton corner may be other than a straight line and such structure is contemplated as falling within the invention.

Although the foregoing description is necessarily of a detailed character, in order that the invention may be completely set forth, it is to be understood that the specific terminology is not intended to be restrictive or confining, and that various rearrangements of parts and modifications of detail may be resorted to without de-

parting from the scope or spirit of the invention as herein claimed.

What is claimed is:

5 1. A folded paper box comprising side panels and end panels, an end flap extending from one end of one of said end panels, a substantial portion of said end flap being equal in width to the associated end panel, means attached to said side panels to form the top of said box, the portion of 10 said top adjacent said end flap having formed therein a top flap, said top flap being articulated to said top along a line that is parallel to and closely adjacent the end of said end flap and stops short of each side panel, said top flap having sides free of said top extending from each end of said line of articulation substantially to the associated corners of the box, said end flap overlying said top flap and underlying the portions of 15 said top disposed at each side of said top flap.

20 2. A folded paper box comprising side panels and end panels, an end flap extending from one end of one of said end panels, a substantial portion of said end flap being equal in width to the associated end panel, said end flap being folded across the top of said box, means attached to said side panels to form the top of said box, the portion of said top adjacent said end flap having formed therein a top flap, said top flap being articulated to said top along a line that is parallel to and closely adjacent the end of said end flap and stops short of each side panel, said top flap having sides formed by fracture lines in said top extending from each end of said line of articulation substantially to the associated corners of 25 the box, said top flap overlying said end flap and being glued thereto, said end flap being positionable to overlie said top flap and underlie the portions of said top disposed at each side of said top flap.

30 3. A folded paper box comprising side panels and end panels, an end flap extending from one end of at least one of said end panels, a substantial portion of said end flap being equal in width to the associated end panel, said end flap being folded across the top of said box, means attached to said side panels to form the top of said box, the portion of said top adjacent said end flap having formed therein a top flap, said top flap being articulated to said top along a line that is parallel to and closely adjacent the end of said end flap and stops short of each side panel, said top flap having sides free of said top extending from each end of said line of articulation substantially to the associated corners of the box, said end flap overlying said top flap and underlying the portions of said top disposed at each side of said top flap, and a length of thin adhesive tape overlying and attached to the exposed portion of said end flap and to said top adjacent said end flap.

35 4. A folded paper box comprising side panels and end panels, an end flap extending from one end of at least one of said end panels, a substantial portion of said end flap being equal in width to the associated end panel, said end flap being folded across the top of said box, means attached to said side panels to form the top of said box, the portion of said top adjacent said end flap having formed therein a top flap, said top flap being articulated to said top along a line that is parallel to and closely adjacent the end of said end flap and stops short of each side panel, said top flap having sides formed by fracture lines in said top extending from each end of said line of articulation substantially to the associated

corners of the box, said top flap overlying said end flap and being glued thereto, said top flap being arranged for separation from said end flap and said top by parting the material along said fracture lines, said end flap being deformable for lifting clear of said top and for insertion beneath top segments disposed to each side of said top flap, said top segments thereafter overlying said top flap.

5. In a container, a paper panel forming a wall of said container, a closure for said panel, said closure comprising a first flap generally rectangular in shape and articulated along one edge to said panel, a second flap of generally trapezoidal configuration, said second flap being articulated along the shorter of its two parallel sides, the line of articulation of said second flap being parallel to that of said first flap and spaced therefrom by

the width of said first flap measured from its line of articulation, the line of articulation of said second flap being substantially centered with respect to that of said first flap so that when said flaps are in contact said first flap extends past both sides of said second flap.
